PHOTOGRAPHIC DEVELOPERS

Maynard S. Raasch, Wilmington, Del., assignor
to E. I. du Pont de Nemours and Company,
Wilmington, Del., a corporation of Delaware

No Drawing. Application June 16, 1950,
Serial No. 168,651

6 Claims. (Cl. 260—518)

1

This invention relates to a new class of aromatic amines. More particularly, this invention relates to a new class of nuclear-substituted p-phenylenediamines which are particularly useful for photographic purposes and to developer compositions containing such compounds.

p-Phenylenediamine and its N-dialkyl derivatives are well-known photographic developers, both for black and white and for color images. However, the known compounds of this type have several defects, one being that these diamines are not highly soluble in the developing solution. Another defect is their staining or fogging tendency on photographic emulsions. Still another defect is their irritating action on the skin of most persons. Moreover, in color development processes, the p-phenylenediamines sometimes do not produce the desired color in the final image. Consequently, numerous derivatives of p-phenylenediamine have been proposed in the technical literature in attempts to overcome these various defects. For example, the hydrogen atoms in the alkyl groups of the N-alkyl-substituted phenylenediamines have been replaced by solubilizing groups such as alkylene or arylene radicals having attached thereto carboxylic or sulfonic acid groups, or the hydrogens in the phenylene nucleus have been replaced by hydroxyalkyl groups or by alkyl groups joined to the nucleus through hetero atoms such as oxygen, nitrogen, or sulfur. While sulfonic and carboxylic acid groups are effective solubilizing radicals on p-phenylenediamine, it is known that the attachment of such groups to the phenylene ring causes a serious decrease in the developing power of the resulting nuclear-substituted phenylenediamine and renders the compound unsuitable for use in photographic developing solutions.

Novel nuclear-substituted p-phenylenediamines are provided by this invention which possess high solubility in aqueous developing solutions, low staining or fogging tendency, low irritancy to human skin, and desirable spectral characteristics, together with an unusually high level of photographic developing activity.

The new compounds of this invention are p-phenylenediamines having a carboxyl group joined to the benzene ring through a chain of one to six carbon atoms in an alkylene radical, and having at least one alkyl group attached to one of the amino nitrogen atoms. Compounds of this type which are particularly effective as photographic developers have the carboxyl group separated from the phenylene nucleus by a chain of at least two carbon atoms in the alkylene

2

group. The high photographic developing activity of the novel compounds of this invention is entirely unexpected in view of U. S. Patent 2,163,166 which teaches that attachment of carboxylic or sulfonic acid groups to the p-phenylenediamine nucleus excessively weakens the developing activity of the compounds.

The new free acid compounds of this invention have the following general formula:

wherein R¹ is hydrogen or an alkyl radical, R² is an alkyl radical, and R is an alkylene radical having a chain of from one to six carbon atoms separating the carboxyl group from the benzene ring. Compounds of this type which are preferred as photographic developers are those in which the total number of carbon atoms in the alkyl groups R¹ and R² is between 2 and 24, in which there is a chain of at least two carbon atoms in the alkylene radical separating the carboxyl group from the phenylene nucleus and in which R is attached to the phenylene ring in a position ortho to the —NH₂ group. Suitable specific radicals for R¹ and R² include methyl, ethyl, isopropyl, n-propyl, isobutyl, n-butyl, n-hexyl, n-heptyl, n-octyl, n-decyl and n-dodecyl. The alkali metal salt and especially the sodium and potassium salts of the above acids constitute important salts of the invention.

The compounds are prepared by various methods, the particular method in any specific case being dependent on the structure and size of the alkylene group in the compound being prepared. Thus, a p-phenylenediamine having a carboxyl separated from the phenylene ring by the methylene group is conveniently prepared by reacting isatin with hydrazine, heating the resulting hydrazone to form oxindole, nitrating the oxindole to 5-nitrooxindole, reducing the nitro group and alkylating, e. g., ethylating, the nitro-oxindole to 5-diethylaminooxindole, and heating this product under pressure with barium hydroxide to form the barium salt of 2-amino-5-diethylaminophenylacetic acid. A p-phenylenediamine having a carboxyl group separated from the phenylene nucleus by an alkylene chain of two carbon atoms is prepared by condensing m-nitrobenzaldehyde with malonic acid, reducing the re-

sulting m-nitrocinnamic acid to m-aminocinnamic acid with ferrous hydroxide, then alkylating with, for example, ethyl iodide to m-diethylaminocinnamic acid, reducing to m-diethylaminohydrocinnamic acid, nitrosating with sodium nitrite and hydrochloric acid to 2-nitroso-5-diethylaminohydrocinnamic acid, and finally reducing this product in alkaline solution to the sodium salt of 2-amino-5-diethylaminohydrocinnamic acid. A p-phenylenediamine having a carboxyl group separated from the phenylene nucleus by an alkylene chain of 4 carbon atoms is prepared by condensing m-nitrobenzaldehyde with acetaldehyde, condensing the resulting m-nitrocinnamaldehyde with malonic acid to form m-nitrocinnamalactic acid, then reducing this product with ferrous sulfate to m-aminocinnamalactic acid, alkylating, e. g., with ethyl iodide, to m-diethylaminocinnamalactic acid, reducing catalytically to δ -(m-diethylaminophenyl)-valeric acid followed by nitrosation and reduction of the nitroso group. A p-phenylenediamine having a carboxyl group separated from the phenylene nucleus by an alkylene chain of six carbon atoms is prepared in the same way as that having an alkylene chain of four carbon atoms with the single exception that the m-nitrocinnamaldehyde obtained as an intermediate is reacted with a second molecule of acetaldehyde before being condensed with malonic acid.

The invention is illustrated in further detail by the following examples in which the proportions of ingredients are expressed in parts by weight unless otherwise noted.

EXAMPLE I

BARIUM 2-AMINO-5-DIETHYLAMINOPHENYLACETATE

A. 5-aminooxindole

To a mixture of 200 parts of stannous chloride and 238 parts of concentrated hydrochloric acid heated to near the boiling point is added 50 parts of 5-nitrooxindole (prepared as described by Sumpter, Miller, and Magan, J. Am. Chem. Soc. 67, 499 (1945)) in portions. The mixture is heated for $\frac{1}{2}$ hour on a steam bath and then diluted to about 3,000 parts. A solution of 120 parts of NaOH in 240 parts of water is added to the solution and hydrogen sulfide is passed in until the tin ions are completely precipitated. The precipitate is filtered off, washed with water, and the filtrate evaporated to about 500 parts, whereupon 18 parts of concentrated NH₄OH is added. Needles of 5-aminooxindole separate, a yield of 25 parts being isolated. These needles, after being recrystallized from alcohol and again from water, have a melting point of 190-195° C.

B. 5-diethylaminooxindole

A mixture of 20 parts of 5-aminooxindole, 50 parts of water, 41 parts of ethanol, and 21.5 parts of ethyl iodide is heated to the boiling point in a reaction vessel fitted with a reflux condenser for 1 hour. After cooling the reaction mixture slightly there is added 5.4 parts of NaOH dissolved in 10 parts of water and 21.5 parts of ethyl iodide after which the mixture is again heated under reflux for one hour. A final addition of 5.4 parts of NaOH is made, and refluxing is continued for another $\frac{1}{2}$ hour. The ethanol is boiled off and the product separates as an oil which crystallizes on cooling. The yield of 5-diethylaminooxindole is 23 parts, corresponding to 86% of the theory. The product after recrystallization from ethyl acetate melts at 126-128° C.

C. Barium 2-amino-5-diethylaminophenylacetate

A mixture of 18 parts of 5-diethylaminooxindole, 30 parts of barium hydroxide octahydrate, and 200 parts of water is heated in a pressure reactor at 150° C. for 15 hours. From the cooled reaction product the sparingly soluble barium salt of 2-amino-5-diethylaminophenylacetic acid is separated by filtration and washed first with water and then with ethanol. A yield of 17 parts (66% of the theoretical) is obtained. The salt is recrystallized by dissolving it in methanol, adding ethanol and boiling to remove the methanol.

Anal. calcd. for (C₁₂H₁₇O₂N₂)₂Ba·H₂O: N, 9.37%. Found: N, 9.35%, 9.44%.

The barium salt is readily soluble in alkaline carbonate developing solutions from which the insoluble barium carbonate formed as a by-product can be removed by filtration, and it has good developing activity.

EXAMPLE II

SODIUM 2-AMINO-5-DIETHYLAMINOHYDROCINNAMATE

A. m-Diethylaminocinnamic acid

A solution of 75 parts of m-aminocinnamic acid (prepared by condensing m-nitrobenzaldehyde with malonic acid by the method of Slotta, Ber. 68B, 187 (1935) and reducing the product with ferrous hydroxide by the method of Gabriel, Ber. 16, 2038 (1883)) and 18.4 parts of NaOH in 100 parts of water and 41 parts of ethanol is placed in a reaction vessel fitted with a reflux condenser, 72 parts of ethyl iodide is added and the mixture is heated under reflux for 1 hour. A solution of 18.4 parts of NaOH in 30 parts of water and 76 parts of ethyl iodide are added and the refluxing is continued for another hour. A final 18.4 parts of NaOH in 30 parts of water is added and the heating continued for another hour at reflux temperature. The resulting solution is cooled and the m-diethylaminocinnamic acid is precipitated by the careful addition of acetic acid. Recrystallization of this acid from dilute ethanol gives 75 parts, corresponding to a yield of 73% of the theoretical, of yellow needles melting at 128-131° C.

B. Sodium m-diethylaminohydrocinnamate

A mixture of 38 parts of m-diethylaminocinnamic acid, 7 parts of sodium hydroxide, 100 parts of water, and 5 parts of nickel alloy skeleton catalyst is charged into a pressure reactor capable of being agitated, and hydrogenated at 1,000-2,000 lb./sq. in. hydrogen pressure at 75° C. for two hours. The product is filtered, the filtrate evaporated to dryness and the residue used without further purification.

C. 2-nitroso-5-diethylaminohydrocinnamic acid

A mixture of 42 parts of sodium m-diethylaminohydrocinnamate, 60 parts of concentrated hydrochloric acid and 100 parts of water is cooled to 0° C. and stirred in a reaction vessel. To this mixture is added dropwise 12.5 parts of sodium nitrite in 20 parts of water, the reaction mixture being held at a temperature below 3° C. The mixture is allowed to stand for one hour, and the resulting slurry of yellow hydrochloride which is formed is dissolved by diluting the mixture to about 450 parts with water. The salt is converted to the free amino acid by adding 40 parts of sodium acetate in 60 parts of water. The green nitroso compound separates in crys-

talline form, amounting to a yield of 37 parts, and melting at 136° C. After crystallization from methanol the 2-nitroso-5-diethylaminohydrocinnamic acid melts at 137° C.

Anal. calcd. for $C_{13}H_{15}N_2O_3$: N, 11.19%. Found: N, 11.17%, 11.21%.

D. Sodium 2-amino-5-diethylaminohydrocinnamate

A solution of 34 parts of 2-nitroso-5-diethylaminohydrocinnamic acid and 5.5 parts of NaOH in 150 parts of water is charged into a pressure reactor with 5 parts of nickel alloy skeleton catalyst, and heated at 60° C. under 1,000-2,000 lb./sq. in. hydrogen pressure for 3 hours. After removing the catalyst from the reaction mixture by filtration, the filtrate is adjusted to a pH of 9.8 with sodium carbonate and then evaporated to dryness under reduced pressure. The residue is dissolved in methanol, filtered, evaporated to small volume and precipitated out in crystalline form by the slow addition of diethyl ether. A yield of 27 parts, corresponding to 84% of the theoretical, of sodium 2-amino-5-diethylaminohydrocinnamate is obtained. This compound is readily soluble in aqueous photographic developing solutions, has very good photographic developing activity, and is no more irritating to skin than the common black and white developer p-hydroxymethylaniline, and is less irritating than p-aminodiethylaniline. This low degree of irritancy is predicated on the results of tests on guinea pigs in which the intradermal injection of sodium 2-amino-5-diethylaminohydrocinnamate produced no more reaction than similar injections of p-hydroxymethylaniline.

EXAMPLE III

SODIUM 2-AMINO-5-DIMETHYLAMINOHYDROCINNAMATE

A. m-Dimethylaminocinnamic acid

A mixture of 41 parts of m-aminocinnamic acid, 10 parts of sodium hydroxide, 60 parts of water, 24 parts of methanol and 38 parts of methyl iodide is placed in a reaction vessel fitted with a reflux condenser and heated to reflux temperature for 45 minutes. There is then added a solution of 10 parts of sodium hydroxide in 25 parts of water, and, after cooling, 38 parts of methyl iodide. The mixture is again heated to reflux temperature for 45 minutes, then another 10 parts of NaOH in 25 parts of water is added after which the mixture is refluxed for another 45 minutes. The reaction mixture is neutralized with hydrochloric acid whereupon m-dimethylaminocinnamic acid precipitates as the inner salt. This salt is recrystallized from dilute ethanol. There is also formed under the above reaction conditions the quaternary ammonium iodide which is thermally decomposed to m-dimethylaminocinnamic acid by heating at 220° C. for 5 minutes. On recrystallization from dilute ethanol the m-dimethylaminocinnamic acid has a melting point of 127-130° C.

Anal. calcd. for $C_{11}H_{13}NO_2$: N, 7.33%. Found: N, 7.38%, 7.21%.

B. Sodium m-dimethylaminohydrocinnamate

A mixture of 6.6 parts of m-dimethylaminocinnamic acid, 1.4 parts of NaOH, 50 parts of water and 3 parts of nickel alloy skeleton catalyst is placed in a pressure reactor and heated at 75° C. under 1500 lb./sq. in. hydrogen pressure for 2 hours. The resulting product is fil-

tered to remove the catalyst and the filtrate used without further purification in the following steps.

C. 2-nitroso-5-dimethylaminohydrocinnamic acid

To the filtered reaction product of step B is added 11.9 parts of concentrated hydrochloric acid and the mixture cooled to 0° C. To this mixture is added dropwise below the surface a solution of 2.5 parts of sodium nitrite in 5 parts of water, and the resulting mixture is allowed to stand in ice for 1 hour. The product is warmed to dissolve the separated solids and then a solution of 16 parts of sodium acetate in 40 parts of water is added. A brown solid separates which is filtered off and washed with water. The washed solid, amounting to 5.6 parts, is dissolved in ethanol to form a green solution from which well-formed, brown needles of 2-nitroso-5-dimethylaminohydrocinnamic acid separate. This compound has a melting point of 167° C. with decomposition.

Anal. calcd. for $C_{11}H_{14}N_2O_3$: N, 12.61%. Found: N, 12.38%, 12.68%, 12.91%.

D. Sodium 2-amino-5-dimethylaminohydrocinnamate

A mixture of 2.6 parts of 2-nitroso-5-dimethylaminohydrocinnamic acid, 0.47 part of NaOH and 50 parts of water is charged into a pressure reactor and heated at 60° C. under 1500 lb./sq. in. hydrogen pressure for two hours. The reaction mixture is filtered, the filtrate evaporated to dryness under reduced pressure, and the residue taken up with methanol, treated with decolorizing carbon, filtered, evaporated to small volume and the salt precipitated by slow addition of diethyl ether. There is obtained 2.64 parts of sodium 2-amino-5-dimethylaminohydrocinnamate. This compound is soluble in water and forms photographic developing solutions of good activity.

EXAMPLE IV

SODIUM δ -(2-AMINO-5-DIETHYLAMINOPHENYL)-VALERATE

A. m-Nitrocinnamalacetic acid

A mixture of 50 parts of m-nitrocinnamaldehyde (prepared as described by Gohring, Ber. 18, 720 (1885)), 30 parts of malonic acid and 29.5 parts of pyridine is placed in a reaction vessel fitted with a reflux condenser and heated at reflux temperature for 6 hours. On cooling to 10° C. 18 parts of yellow crystals separate and they are removed by filtration. The filtrate is poured into water and sulfuric acid added to complete the precipitation, whereupon an additional quantity of solid is obtained which is purified by dissolving in dilute alkali, treating with charcoal and precipitating with sulfuric acid. An additional 18 parts of product is obtained in this step of the process. On recrystallization of both of these fractions there is obtained 15 parts of m-nitrocinnamalacetic acid melting at 238-243° C., obtained mostly from the fraction which crystallized from the original pyridine reaction mixture. Additional material melting at a lower temperature is also obtained, and this is believed to consist of geometric isomers of m-nitrocinnamalacetic acid.

Anal. calcd. for $C_{11}H_9NO_4$: N, 6.39%. Found: N, 6.23%.

B. m-Aminocinnamalacetic acid

A solution of 5.8 parts of concentrated ammo-

nium hydroxide and 20 parts of *m*-nitrocinnamalactic acid in 30 parts of water is added to a mixture of 165 parts of ferrous sulfate, 150 parts of water and 72 parts of concentrated ammonium hydroxide. This mixture is heated to the boiling point and left on a steam bath for one hour. The product is then made distinctly alkaline with ammonium hydroxide, filtered while still hot, and the filter cake washed with hot water, the ammonium salt being rather sparingly soluble. The filtrate is reduced in volume to about 500 parts and the *m*-aminocinnamalactic acid is precipitated from the solution with acetic acid. Fifteen parts of crude product is obtained which on recrystallization from ethanol amounts to 11 parts, corresponding to a yield of 64% of the theoretical, of yellow needles of *m*-aminocinnamalactic acid melting at 177-178° C.

Anal. calcd. for $C_{11}H_{11}NO_2$: N, 7.40%. Found: N, 7.40%, 7.30%.

C. *m*-Diethylaminocinnamalactic acid

To a solution of 10.7 parts of *m*-aminocinnamalactic acid and 2.3 parts of NaOH in 25 parts of water and 20.5 parts of ethanol is added 9 parts of ethyl iodide and the mixture is heated under reflux for 0.8 hour. An additional 2.3 parts of NaOH in 5 parts of water and 9 parts of ethyl iodide are added and the refluxing is continued for another 0.8 hour. After a final addition of 2.3 parts of NaOH and further refluxing for 0.5 hour, the solution is cooled and the *m*-diethylaminocinnamalactic acid is precipitated by the addition of acetic acid. On recrystallization of the product from dilute ethanol there is obtained 9.7 parts, corresponding to a yield of 70% of the theoretical, of bright yellow crystals melting at 120-122° C.

Anal. calcd. for $C_{15}H_{19}NO_2$: N, 5.71%. Found: N, 5.54%, 5.36%.

D. Sodium δ -(*m*-diethylaminophenyl) valerate

A solution of 9.5 parts of *m*-diethylaminocinnamalactic acid and 1.6 parts of NaOH in 120 parts of water is charged into a pressure reactor with 5 parts of nickel alloy skeleton catalyst. The mixture is heated at 75-80° C. under 2,000 lb./sq. in. hydrogen pressure for 2.5 hours. After the catalyst is removed by filtration the reaction mixture is used directly in the following step.

E. 2-(δ -carboxybutyl)-4-diethylamino-4'-nitroazobenzene

The solution from step D above is mixed with 8.3 parts of concentrated hydrochloric acid with added to a diazonium solution prepared from 5.7 parts of *p*-nitroaniline, and 18 parts of sodium acetate is then added and the mixture allowed to stand 1 hour at 20° C. There is obtained by filtration 12 parts of 2-(δ -carboxybutyl)-4-diethylamino-4'-nitroazobenzene, corresponding to 77% of the theoretical. Recrystallization from methanol gives 10.8 parts of maroon needles melting at 173-175° C.

F. Sodium δ -(*amino*-5-diethylaminophenyl)-valerate

A mixture of 9.5 parts of the azo dye obtained in step E above, 175 parts of water, 0.95 part of NaOH and 2 parts of palladium-on-charcoal catalyst is charged into a pressure reactor and heated at 65-70° C. under 2,000 lb./sq. in. hydrogen pressure for 2 hours. The reaction mixture is filtered to remove the catalyst and the filtrate is evaporated to dryness under reduced pressure.

The residue is warmed with 60 parts of acetone, cooled, filtered, and washed with acetone to remove *p*-phenylenediamine. The residue of sodium δ -(*amino*-5-diethylaminophenyl)valerate is dissolved in a small amount of methanol and precipitated in crystalline form by slowly adding diethyl ether. This compound is easily soluble in water and it forms photographic developing solutions of very good activity.

Anal. calcd. for $C_{15}H_{23}N_2O_2Na \cdot H_2O$: N, 9.20%. Found: N, 9.28%, 8.96%.

EXAMPLE V

BARIUM β -(*2*-AMINO-5-DIETHYLAMINOPHENYL)-BUTYRATE

A. 4-methylhydrocarbostyryl

A mixture of 111 parts of 4-methylcarbostyryl (prepared as described in Organic Syntheses 24, 68 (1944)), 2,450 parts of 2B denatured ethyl alcohol, and 8 parts of palladium-on-carbon catalyst are charged into a pressure reactor and heated at 110-120° C. for 4 hours under 2,000 lb./sq. in. hydrogen pressure. The reaction mixture is filtered to remove the catalyst and the filtrate is evaporated to dryness. The residue is extracted with diethyl ether, the ether extract evaporated to dryness and the residue recrystallized from ethyl acetate. There is obtained 51 parts, corresponding to a 45% yield, of 4-methylhydrocarbostyryl, having a melting point of 92-97° C.

B. 6-nitro-4-methylhydrocarbostyryl

A mixture of 56 parts of 4-methylhydrocarbostyryl and 322 parts of concentrated sulfuric acid is placed in a reaction vessel fitted with a thermometer, stirrer and dropping funnel and surrounded by an ice-salt mixture. To the reaction mixture, maintained at -3 to 0° C., is added dropwise 22.5 parts of fuming nitric acid. After standing in ice for one-half hour the mixture is poured onto 1,000 parts of ice. The solid reaction product is filtered off, washed with water and recrystallized from glacial acetic acid. A yield of 56 parts, corresponding to 78% of the theoretical, of pale yellow needles of 6-nitro-4-methylhydrocarbostyryl, having a melting point of 218-228° C., is obtained.

C. 6-amino-4-methylhydrocarbostyryl

A mixture of 65 parts of iron powder and 110 parts of water is placed in a reaction vessel fitted with a stirrer and heated to 95° C. To this mixture are added 7.1 parts of concentrated hydrochloric acid, and 54 parts of 6-nitro-4-methylhydrocarbostyryl in portions. After all has been added the mixture is stirred and heated at 95° C. for 1 hour. Six parts of sodium bicarbonate and 327 parts of ethanol are then added and the mixture is filtered hot and the residue washed with hot ethanol. Evaporation of the filtrate to dryness, and recrystallization of the residue from dilute methyl alcohol gives 43 parts, corresponding to 94% of the theoretical, of 6-amino-4-methylhydrocarbostyryl, having a melting point of 192-203° C.

D. 6-diethylamino-4-methylhydrocarbostyryl

A mixture of 25 parts of 6-amino-4-methylhydrocarbostyryl, 30 parts of water, 81.6 parts of ethanol and 23 parts of ethyl iodide is heated under reflux for 3/4 hour. There are then added 5.9 parts of NaOH in 10 parts of water and 23 parts of ethyl iodide. After heating under re-

flux for another 3 hours, an additional 5.9 parts of NaOH in 10 parts of water is added and the heating continued for 1 hour under reflux. The ethanol is distilled off the reaction mixture, whereupon the product separates as an oil which crystallizes on cooling. There is obtained 31 parts, corresponding to a yield of 94% of the theoretical, of 6-diethylamino-4-methylhydrocarbostyryl. On recrystallization from dilute ethanol this compound has a melting point of 125-128° C.

E. Barium β -(2-amino-5-diethylaminophenyl)-butyrate

A mixture of 24 parts of 6-diethylamino-4-methylhydrocarbostyryl, 22 parts of barium hydroxide octahydrate, and 200 parts of water is heated in a closed reaction vessel at 150° C. for 15 hours. The reaction mixture is filtered and 15 parts of unreacted starting material is removed. Barium hydroxide is then removed from the filtrate by the addition of solid carbon dioxide. The solution is then filtered from the insoluble barium carbonate and the filtrate is evaporated to dryness to give the barium salt of β -(2-amino-5-diethylaminophenyl)butyric acid. This product has rapid developing action when used as a photographic developer.

In addition to the compounds shown in the examples, this invention includes as new products any p-phenylenediamines having a carboxyl group joined to a carbon atom of the phenylene nucleus through a chain of 1 to 6 carbon atoms in an alkylene radical, having a free $-NH_2$ group and having at least one alkyl group attached to the other amino nitrogen atom. Other specific compounds of this type, which are included by the general formula:

wherein R is an alkylene radical having a chain of 1 to 6 carbon atoms separating the carboxyl group from the benzene ring, R¹ is a hydrogen atom or an alkyl radical and R² is an alkyl radical, are: zeta-(2-amino-5-diethylamino)-enanthic acid, 2-amino-5-diisobutylaminohydrocinnamic acid, 2-amino-5-di-n-octylaminohydrocinnamic acid, 2-amino-5-di-n-dodecylaminophenylacetic acid, and 2-monoethylaminino-5-aminohydrocinnamic acid. Compounds in which the carboxyl group readily unites with the free amino group to form a cyclic amide are conveniently isolated as a salt to prevent this reaction.

The compounds of this invention are particularly useful as color developers because of the desirable combination of properties which they possess. They are highly soluble in photographic developer solutions and have low staining or fogging tendencies. They are also especially desirable since they exhibit decreased irritancy to skin in comparison with the usual N,N-dialkyl-p-phenylenediamines. These compounds also possess a high level of developing activity, those compounds in which the carboxyl group is separated from the phenylene nucleus by a chain of two or more carbon atoms being especially preferred because they are the most active from this standpoint. The carboxyalkyl groups in the

products of this invention cause a bathochromic shift in the developed dyes in color-former photographic emulsions of 7-17 millimicrons greater than the shift obtained in such color films by conventional developers having a methyl group attached to the phenylene nucleus. The compounds of this invention may be used in developing compositions containing color formers for color development of exposed silver halide contained either in the conventional gelatin or in a synthetic resin carrier, and of film-containing immobile color former incorporated in the film, particularly film having, as the silver halide binder, polyvinyl acetals of color-forming aldehydes as described in U. S. Patent 2,397,864. The nuclear-substituted p-phenylenediamines of this invention can be employed in solution with conventional developing ingredients including alkaline materials, e. g., sodium or potassium carbonate, borate, phosphate or hydroxide; water-soluble sulfites, e. g., ammonium sulfite, sodium sulfite and potassium sulfite. They may also be employed with such ingredients as hydroxylamine, amines, etc.

In addition to their use in photographic developing compositions which constitutes one aspect of this invention, the nuclear-substituted p-phenylenediamines of this invention, having a carboxyl group attached through an alkylene group to the phenylene nucleus, are useful as rubber accelerators, antioxidants for gasoline, stabilizers for halogen-containing plastics, azo and azomethine dye intermediates, etc., and as intermediates for preparing light-sensitive diazo-type materials.

As many widely different embodiments of this invention can be made without departing from the spirit and scope thereof, it is to be understood that the invention is not to be limited except as defined by the claims.

What is claimed is:

1. The chemical compounds taken from the group consisting of compounds of the formula:

45

wherein R¹ is a member taken from the group consisting of hydrogen and alkyl radicals of 1 to 12 carbon atoms, R² is an alkyl radical of 1 to 12 carbon atoms, and R is a saturated aliphatic hydrocarbon radical having an alkylene radical of 1 to 6 carbon atoms joining the benzene nucleus and COOH group, and their alkali metal salts.

2. The chemical compounds of the formula:

65

wherein R¹ is an alkyl radical of 1 to 12 carbon atoms and R'' is a polymethylene radical of 2 to 6 carbon atoms.

11

3. The chemical compound of the formula:

4. The chemical compound of the formula:

5. The chemical compound of the formula:

12

6. The chemical compound of the formula:

5
